UNITED STATES PATENT OFFICE.

GEORGE W. BETTES, OF SPARTA, MICHIGAN.

ROAD MARKER.

Application filed May 8, 1924. Serial No. 711,784.

This invention relates to road markers, to be hand propelled for applying short 55 marks on the road. particularly to those adapted to apply traffic marks to the surface of cement or other hard surfaced roads. It is becoming customary to mark the highways with a white stripe extending along the center of the road for the purpose of defining the right and left side to direct the traffic thereon and also to mark street intersections and parking spaces with 10 white lines on the road in various ways.

It is the object of this invention to provide a device which will carry a considerable quantity of the paint used for marking and to apply this paint in a smooth and well defined mark upon the road. The device is adapted to be attached to an automobile or other vehicle by which it may be drawn to traverse the road for marking long stretches which often extend several miles and the device 15 may also be used as a hand propelled marker for marking short lines such as those used at street intersections, parking spaces, etc.

The device is provided with means for 20 evenly distributing the paint upon the roller which transfers it to the road surface, it has means for regulating the quantity of paint applied, the transfer roller is adapted to be raised from contact with the road surface 25 whereby the device is made inoperative, the structure is so arranged that it may be easily disassembled for cleaning and various novel features of construction and arrangements are provided as will more fully appear after 30 a thorough understanding of the invention is had from the following description, reference being had to the accompanying drawings in which:

Fig. 1, is a side elevation of the device 40 embodying this invention.

Fig. 2, is a fragmentary elevation viewed from the opposite side showing details of construction, principally the feed pump driving means.

Fig. 3, is a sectional plan of the device taken on the line 3—3 of Fig. 1.

Fig. 4, is an enlarged fragmentary elevation of parts of the transfer roller and spreading roller also showing the paint feeding nozzle.

Fig. 5, is a transverse fragmentary section on the line 5—5 of Fig. 4, and Fig. 6 is a reduced elevation of a modified form of structure illustrating the device adapted

Like reference numbers refer to like parts in all of the figures. This device is intended to be mounted for operation at the side of an automobile adjacent one of the 60 running boards 1 thereof. A bar 2 is attached to the running board and to the frame of the automobile extends beyond the running board and has brackets 3 to which the frame of the marker is pivotally attached. 65 The marker has a frame composed of the horizontal bars 4, the vertical bars 5 and the brace 6, these being joined together by cross bars 7. The paint transfer roller 8 and the spreading roller 9 are mounted upon 70 and between two spaced apart horizontal bars 4. The transfer roller rotates upon a fixed axle 10 and the spreading roller has an axle 11 journaled in sliding boxes 12 which are moved toward the transfer roller by the tension springs 13. The springs 13 are attached to the boxes 12 at one end 75 to adjustable hooks 14 at the other end. The shanks of the hook are screw threaded and pass through brackets 15 and are provided with nuts 16 by means of which the tension of the springs 13 may be regulated.

A paint reservoir 17 is mounted at the upper part in the frame of the device and has an outlet valve 18 in its bottom from 80 which a hose 19 leads to a pump 20. The pump 20 is preferably of the type known as a gear pump and is fastened to a bracket 21 extending from the frame member 5 and the driving shaft of the pump is provided 85 with a pinion 22 which meshes with and is driven by a gear 23 attached to the transfer roller 8. A hose 24 leading from the outlet of the pump communicates with the paint feeding nozzle 25 which is located between 90 the rollers 8 and 9 directly above the contact point of these rollers and has an opening 26 in its lower side through which the paint flows onto the rollers. The nozzle is supported by brackets 27 which extend upward from the horizontal bars 4 of the frame.

The periphery of the paint transfer rollers 8 is covered with felt or some like absorbent material 8^a which will readily absorb the 105 paint and transfer it to the surface of the road which the roller engages. The periphery of the spreading roller 9 is covered

with rubber or some impervious material 9^A which will not absorb the paint and which rotates in engagement with the felt covering of the transfer roller. The width of the felt covering of the transfer roller is made the same as the width of the line or mark desired on the road and the rubber covering of the spreading roller is the same width.

The device is pivotally connected at its front end with the brackets 3 by the bolt 28 and in operative position its rear end is supported by the transfer roller which engages the road. Pulleys and rope commonly known as block and tackle 29 are attached to the rear end of the frame and also to some convenient portion of the automobile and may be manually operated to raise the transfer roller from the road which makes the device inoperative.

In operation the automobile with the marker attached thereto as described, is driven along the road with the transfer roller in engagement with the surface thereof, and rotated by its contact with the road, and as the roller turns the gear 23 attached thereto meshing with the pinion 22 drives the feed pump 20 which takes paint from the reservoir 17 through the valve 18 and hose 19 and delivers the paint through the hose 24 to the feed jet 25. Since the pump is driven by the transfer roller its speed will be in direct proportion to that of the roller and consequently the amount of paint delivered by the pump to the feed nozzle will also be in direct proportion to the speed of the roller. The paint is delivered from the feeding nozzle through the opening 26 and deposited upon the transfer roller and spreading roller near their point of contact and the pressure of the spreading roller against the felt surface of feeding roller evenly distributes the paint over the felt surface and forces it into the absorbent felt from which it is applied upon the road surface as the roller traverses the same. The tension springs 13 which hold the spreading roller into engagement with the transfer rollers are adjusted so that the spreading roller presses against the transfer roller with the proper tension to properly distribute the paint. The valve 18 may be used to stop the flow of paint entirely from the reservoir or to regulate the amount which will be admitted to the pump.

When the device is not to be operated the transfer roller 8 is raised from the road by the block and tackle 29 or by such other means as may be substituted for the block and tackle, and this makes the device inoperative as the roller will not rotate and the pump will not operate and consequently no paint will flow from the reservoir.

The modified structure shown in Figure 6 which is intended for manual operation differs from the above described device only

in the addition of the front wheels 30, the standard 31 and the handles 32. When this device is operated it is preferably rolled and supported entirely upon the transfer roller, the front wheels 30 being raised from the road. The device may be inoperative by raising the transfer roller from the road and supporting the device upon the front wheels 30 upon which it may be moved from place to place. The standard 31 which is pivotally attached to the frame may be swung downward to support the device with the transfer roller raised from the road, in which position it will stand alone.

I claim:

1. A road marker comprising a transfer roller having its periphery covered with absorbent material and adapted to be rotated by frictional engagement with the surface of the road, a spreading roller having its periphery covered with non-absorbent material and adapted to rotate by frictional engagement with the transfer roller and means for applying paint to said absorbent material on the periphery of the transfer roller.

2. A road marker comprising a frame adapted to be pivotally connected at its forward end and to a vehicle, a transfer roller mounted near the rear of said frame and adapted to be rotated by frictional engagement with the surface of the road, a spreading roller mounted on the frame and adapted to be rotated by frictional engagement with the transfer roller, means actuated by rotation of the transfer roller for feeding paint to the periphery of the transfer roller and means for lifting the rear end of the frame whereby the transfer roller is raised from engagement with the road.

3. A road marker comprising a frame adapted to be pivotally connected to a vehicle, a transfer roller mounted on the frame and adapted to be rotated by frictional engagement with the road, a pump driven by the transfer roller, means for supplying paint to the pump, means for delivering paint from the pump to the periphery of the transfer roller and means for lifting the frame to raise the transfer roller from engagement with the road.

4. A road marker comprising a frame adapted to be pivotally connected to a vehicle, a transfer roller mounted on the frame and adapted to be rotated by frictional engagement with the road, a spreading roller slidably mounted on the frame and adapted to engage the periphery of the transfer roller, adjustable means for exerting spring pressure against the journals of the spreading roller to press it against the transfer roller, a feeding nozzle located above the point of contact between the two rollers, a pump actuated by the transfer roller, a paint reservoir mounted on the frame, a

- hose leading from the said reservoir to the inlet of said pump, a hose leading from the outlet of said pump to the said feeding nozzle and means for raising the frame to lift the transfer roller from contact with the road.
5. A road marker comprising a frame having supporting wheels at its forward end, a transfer roller mounted near the rear of the frame and adapted to roll upon the surface of the road, a pump actuated by rotation of the transfer roller, a spreading roller mounted on the frame and held into frictional engagement with the transfer roller, a feeding nozzle over the transfer roller, a reservoir mounted on the frame, a hose connecting the reservoir with the inlet of the pump and a hose connecting the outlet of the pump with the nozzle.
10. A road marker comprising a frame, 55 a support for the forward end of the frame adapted to be moved over a road surface, a paint reservoir mounted on the frame, a transfer roller detachably mounted near the rear end of the frame and adapted to roll over the road surface, a spreading roller mounted on the frame and held into frictional engagement with the transfer roller, a pump fixed to the frame, gears on the pump and transfer roller meshing together whereby the pump is actuated by rotation of said transfer roller, a nozzle over the point of contact between the transfer roller and the spreading roller, means for conducting paint from the reservoir to the 60 pump, and means for conducting paint passed by the pump to the periphery of the roller.
15. A road marker comprising a roller adapted to engage the road surface and to be rolled over the same, a pump actuated by rotation of the roller as it is rolled over the road, means for supplying paint to the pump, and means for depositing the paint passed by the pump to the periphery of the roller.
20. A road marker comprising a roller adapted to engage the road surface and to be rolled over the same, a pump actuated by rotation of the roller and at a speed in direct ratio to the speed of the roller as it is rolled over the road, means for supplying paint to the pump, and means for depositing the paint passed by the pump to the periphery of the roller.
25. A road marker comprising a roller having its periphery covered with absorbent material adapted to engage the road surface and to be rolled over the same, a pump actuated by rotation of the roller as it is rolled over the road, means for supplying
- paint to the pump, and means for depositing the paint passed by the pump to the periphery of the roller.
30. A road marker comprising a roller adapted to engage the road surface and to be rolled over the same, a pump actuated by rotation of the roller and at a speed in direct ratio to the speed of the roller as it is rolled over the road, means for supplying paint to the pump, and means for depositing the paint passed by the pump to the periphery of the roller.
35. A road marker comprising a roller having its periphery covered with absorbent material adapted to engage the road surface and to be rolled over the same, a pump actuated by rotation of the roller as it is rolled over the road, means for supplying
- paint to the pump, and means for depositing the paint passed by the pump to the periphery of the roller.
40. A road marker comprising a roller having its periphery covered with absorbent material adapted to engage the road surface and to be rolled over the same, a pump actuated by rotation of the roller as it is rolled over the road, means for supplying
- paint to the pump, and means for depositing the paint passed by the pump to the periphery of the roller.
45. A road marker comprising a roller adapted to be rolled over the surface of a road, a spreading roller held in frictional engagement with the first roller, a pump actuated by rotation of the first roller, 50 means for supplying paint to the pump, and means for depositing the paint passed by the pump upon the peripheries of the rollers near their point of contact.
5. A road marker comprising a frame, 55 a support for the forward end of the frame adapted to be moved over a road surface, a paint reservoir mounted on the frame, a transfer roller detachably mounted near the rear end of the frame and adapted to roll over the road surface, a spreading roller mounted on the frame and held into frictional engagement with the transfer roller, a pump fixed to the frame, gears on the pump and transfer roller meshing together whereby the pump is actuated by rotation of said transfer roller, a nozzle over the point of contact between the transfer roller and the spreading roller, means for conducting paint from the reservoir to the 60 pump, and means for conducting paint passed by the pump to the nozzle.
10. A road marker comprising a roller adapted to be rolled over the surface of a road, a spreading roller mounted ahead of 65 the first roller and held into frictional engagement therewith, a pump actuated by rotation of the first roller, means for supplying paint to the pump and means for depositing paint passed by the pump upon 70 the peripheries of the rollers above their point of contact.
11. A road marker comprising a roller adapted to be rolled over the surface of a road, a spreading roller mounted ahead of 75 the first roller and held into frictional engagement therewith, a pump actuated by rotation of the first roller, means for supplying paint to the pump and means for depositing paint passed by the pump upon 80 the peripheries of the rollers above their point of contact.

In testimony whereof I affix my signature.
GEORGE W. BETTES.
